(57) **CLAIM**

We claim the ornamental design for a front portion of a stun gun, as shown and described.

DESCRIPTION

FIG. 1 is a front perspective view of a front portion of a stun gun, showing our new design;

FIG. 2 is a front elevational view of FIG. 1; and,

FIG. 3 is a top plan view of FIG. 1, the bottom plan view being a mirror image thereof.

The broken lines showing a remaining portion of a stun gun depict environmental matter, and form no part of the claimed design. The remaining broken lines shown on the design in the figures represent potential boundary lines for future continuation applications. The rear elevational view constitutes no part of the claimed design.
